INTERNAL-COMBUSTION ENGINE

Arthur Percival Mansoff, Dauphin, Manitoba,
Canada

Application May 8, 1943, Serial No. 436,125

5 Claims. (Cl. 123—69)

My invention relates to internal combustion engines, more particularly having reference to improved charging and scavenging means for the engine cylinders.

In the art to which the invention relates, in the four engine a scavenging stroke of the piston is provided which, however, only partially disposes of the waste gases, while in the two cycle engine the scavenging is very limited. The present invention contemplates improvements in scavenging by which air under pressure is introduced to the cylinder and directed to obtain a thorough discharge of the waste gases.

Additionally in the art air introduced to the cylinders for forming the charge is normally under atmosphere pressure only. It has been proposed in various ways to increase the pressure obtainable either by use of high compression, as in the poppet valve engine, or by supercharging. The within invention provides improvement in the charge by introducing air under pressure to the cylinder by a simplified form of supercharging.

One of the objects of the invention is accordingly to provide improved scavenging means for the cylinder of an internal combustion engine by which air under pressure is introduced to the cylinder at the conclusion of the power stroke to effect discharge of the waste products of combustion through a simultaneously uncovered outlet port.

A further object of the invention is to provide means for so directing the incoming scavenging air as to ensure complete elimination of waste gases.

A still further object of the invention is to provide improved and simplified means for preparing and introducing a charge under pressure to the cylinder in advance of the compression stroke of the engine piston.

Other features and advantages of the invention will become apparent by reference to the accompanying description taken in conjunction with the drawing wherein:

Fig. 1 is a side view in elevation of an engine cylinder and piston with associated elements of which the cylinder and certain parts are in vertical section.

Fig. 2 is a detail view of a part of the engine shown partly broken away and partly in vertical section and providing details of the injector mixer valve, heated vaporizer and check valve.

Having reference to the drawing 1 indicates an engine cylinder which in the present showing is somewhat elongated to accommodate a piston 55

assembly of abnormal length, and 2 a fragment of the crank case to which the cylinder is attached. In the head of cylinder 1 is a spark plug 3.

5 Mounted for reciprocation within the cylinder 1 is a piston assembly that includes a main piston 4 formed with a solid head on each end. The piston 4 is drilled and tapped for mounting a piston rod 5 that is threaded through top and bottom 10 of the piston and secured by a screw 6 through the head of the piston countersunk therein. The piston rod 5 includes an integral enlarged section 7 forming a smaller intermediate piston reciprocating within a complementary bore in a solid center block 8 of the cylinder 1. The piston section 7 is provided with sealing rings as in ordinary piston construction.

In the cylinder 1, below the block 8, is formed a further compression chamber in which is 20 mounted a secondary piston 9 secured to the lower end of piston rod 5, the piston rod having a tapered portion 10 for seating against a complementary opening in the piston 9, and terminating in a threaded end 11 for receipt of a locking nut 12.

25 It will be seen that the cylinder 1 with its integral block 8 is designed as a unit providing two compression chambers, one above the block 8 and the other below said block; the compression chamber above the block is further divided into 30 two compression areas by reason of the piston 4 being closed at the ends, there being a combustion area between the piston and cylinder head in which the charge is compressed and fired, and a compression area between the piston and block 8 35 in which air for the charge is compressed preliminary to forming the charge.

The secondary piston 9 conforms generally to the ordinary piston in common use and is provided with the usual connecting rod 13 and associated 40 pin and crank connections as indicated. There is included a shaft 14 for the electric distributor and pump, the shaft 14 being mounted in a bracket 15 with driving connection to the crank shaft as shown. The secondary piston may be about one 45 half the depth of the main piston.

For scavenging purposes it is proposed to compress and store a charge of air for delivery to the combustion chamber at the conclusion of the power stroke. For this I provide a pipe 16 in which 50 air from the lower section of the cylinder compressed by the upward stroke of secondary piston 9 is held by a check valve 17. The upper end of the pipe 16 discharges into the upper section of the cylinder, designated by numeral 18, and is normally closed by the main piston 4 to be un-

covered at the approximate termination of the down stroke of the piston and to allow the pocketed air to enter to enter the cylinder section 18 and displace the waste gases which are discharged through an exhaust pipe 19.

In order to direct the incoming scavenging air from pipe 16 a lip 20 is provided on the piston 4 in opposing relation to the upper port from pipe 16. This lip is adapted to direct the incoming air from pipe 16 upwards to clear the upper portion of the cylinder of waste gases.

During the downward movement of piston 4 air is compressed in the lower portion of the upper cylinder, indicated by numeral 21, and in the bore of block 8. The cylinder bore in block 8 has an outlet conduit 22 discharging through a pipe 23 into the upper cylinder section 18. Air compressed by cylinder 4 in chamber 21 is stored in the bore of block 8, this bore being evacuated by descent of piston 1. When the upper end of piston 1 uncovers the outlet through pipe 22 the air compressed and stored in the bore of block 8 is released for discharge.

In the pipe 23 is interposed an injector mixer valve and chamber 24 with fuel inlet 25 where the charge is formed to be passed through an exhaust heated vaporizer 26 to discharge into the cylinder section 18 where it impinges on lip 20 for distribution. For the injector mixer valve a chamber 29 provides a float chamber 30 into which fuel inlet 25 discharges and in which a float 31 is hinged in relation to the inlet of a valve chamber 32, fuel from which is sprayed into the main body of chamber 29 under control of a needle valve 33. Discharge from pipe 23 passes into the main body of the chamber 29 to be mixed with the atomized fuel from the chamber 32 and discharged therefrom through the vaporizer 26 into cylinder section 18.

There is further provided in the cylinder 1 an air inlet port 27 for the section 21 and an inlet port 28 for the lower cylinder section.

In the operation of the engine, in the down or power stroke of the piston assembly the air inlet port 27 is first covered by piston 4 and air in the cylinder section 21 is compressed, the bore of block 8 providing a storage chamber for the compressed air.

Continued downward movement of the piston assembly uncovers exhaust port 19 to allow the waste gases in cylinder section 18 to escape. Immediately following this the piston 4 uncovers the inlet port from pipe 16 to allow air stored therein under pressure from the previous upward stroke to escape into the cylinder section 18 and drive the waste gases out through port 19, this action being assisted by the deflection of the air from pipe 16 by lip 20. Compression of air within pipe 16 on the up stroke of the assembly is hereinafter described.

Following the scavenging action the outlet port 22 is uncovered by piston section 1 which is moving downward in conformity with movement of piston 4. This allows air compressed in the lower cylinder section and stored in the bore of block 8 to enter pipe 23 and after passage through mixer valve chamber 24 enters the upper cylinder section 18. This air is under pressure and while some pressure may be relieved before closure of port 19 a considerable pressure will be maintained.

During the downward stroke of the piston assembly a vacuum is formed in the lower cylinder section until released by inlet port 28. On the upward stroke of the piston assembly the air is

compressed into pipe 16 through check valve 17 until required on the next down stroke for scavenging the chamber 18.

The return movement of piston 1 closes the outlet 22. The vacuum created in chamber 21 by the upward movement of piston 4 is relieved when the inlet 27 is uncovered.

The piston movement herein described permits of a two cycle engine performing the functions normally carried out by a four cycle movement since the scavenging is accomplished without any extra piston movement. In addition the charge in the cylinder is under pressure in advance of the pressure stroke of the piston so that greatly increased compression is obtainable.

While I have herein shown in the drawing bare essentials for illustrating and describing the improvements contemplated it is to be understood that the necessary associated parts common in the art would be added in the construction of a working engine including oil pump, generator and other elements.

The within showing is to be taken as a preferred embodiment of my invention but it is obvious that changes in construction of parts and elements would be permissible within the scope of the invention as defined in the appended claims.

What I claim and wish to secure by Letters Patent is:

1. In an internal combustion engine a cylinder providing inlet and exhaust ports, a piston mounted for reciprocation in the cylinder, said piston being closed at the ends, a connecting rod for the piston, a block in the cylinder, said block providing a bore for travel of the connecting rod, and said block being spaced from the cylinder head to provide compression areas above and below the piston, means providing communication from the lower to the upper of said compression areas, and charge forming means in said communicating means.

2. In an internal combustion engine a cylinder providing inlet and exhaust ports, a piston for reciprocation in the cylinder, said piston being closed at the ends, a connecting rod for the piston and an integral piston section on the connecting rod, a block in the cylinder spaced to provide for compression areas above and below the piston, said block providing a bore for reciprocation of the piston section on the connecting rod, a pipe providing communication between the cylinder block bore and the upper compression area of the cylinder, and charge forming means for the pipe.

3. In an internal combustion engine, a cylinder providing inlet and exhaust ports, a piston for reciprocation in the cylinder, said piston being closed at the ends, a connecting rod for the piston and an integral piston section on the connecting rod, a block in the cylinder providing a bore for reciprocation of the connecting rod piston section, said block being spaced from the cylinder head to provide for compression areas above and below the piston, a pipe providing communication between the cylinder block bore and the upper compression area, charge forming means in the pipe, a secondary piston on the connecting rod below the block and forming a compression chamber in conjunction therewith, a scavenging pipe between said last mentioned compression chamber and the upper compression area, and valve means for the scavenging pipe.

4. In an internal combustion engine a cylinder, a block dividing the cylinder to form compres-

sion chambers, one above and one below the block, a piston assembly for reciprocation in the cylinder, said assembly providing a main piston for operation in the compression chamber above the block, and a secondary piston for operation in the compression chamber below the block, and a rod connecting the pistons, the block being bored for travel of said rod, a scavenging pipe providing communication between the cylinder chambers above the pistons, the outlet for said pipe being located to be uncovered at the termination of the power stroke of the main piston, and a check valve in the scavenging pipe by which air compressed by the secondary piston may be

stored in the scavenging pipe for discharge into the cylinder chambers for the main piston.

5. In an internal combustion engine providing a cylinder with piston for reciprocation therein, and a connecting rod for the piston, a block in the cylinder located in relation to the piston and cylinder head to provide for compression areas above and below the piston, said block being bored to form a chamber for storage of air compressed in the lower compression area, a piston on the connecting rod forming a movable closure in the block bore, and a communicating pipe between the block bore and upper compression area.

ARTHUR P. MANSOFF.
